F. J. Fracker of Boston, Mass. asserts.
Tucker Manufacturing Company.
Letters Patent No. 3359. Dated July 17. 1866.
Design for Clock Case.

The Schedule referred to in this Letters Patent and making part of the same.

To all whom it may concern:

Be it known that F. J. Fracker of Boston in the County of Suffolk, and State of Massachusetts have originated and produced a new and ornamental Design for a Clock Case, of which the following is a full and clear description referring back to the accompanying drawings, making part of this Specification.

The Design consists of a base a, having a column b, erected upon it, said column bearing in its face, the dial c, of the clock and being surmounted by a cap d, having an urn or vase e, upon it, the outline or design of the whole being as shown in the drawing.

I claim the design for a Clock Case as shown in the drawing
Witnessed
